US00D946400S

(12) **United States Design Patent** (10) **Patent No.:** **US D946,400 S**
(45) **Date of Patent:** **** Mar. 22, 2022**

(54) **FUNNEL**

(71) Applicant: **CORNERSTONE CM, INC.**, Poland, OH (US)

(72) Inventors: **Michael G. Marantis**, Poland, OH (US); **Richard A. Ponton**, New Milford, CT (US); **Joshua W. Hubbard**, New Milford, CT (US); **Jonathan P. Richards**, Derby, CT (US)

(73) Assignee: **CSCM Management Company LLC**, Poland, OH (US)

(**) Term: **15 Years**

(21) Appl. No.: **29/788,772**

(22) Filed: **Jul. 27, 2021**

Related U.S. Application Data

(63) Continuation of application No. 29/762,912, filed on Dec. 18, 2020, now Pat. No. Des. 926,572, which is a continuation of application No. 29/700,104, filed on Jul. 31, 2019, now Pat. No. Des. 908,486, which is a continuation of application No. 29/625,282, filed on Nov. 8, 2017, now Pat. No. Des. 859,986, which is a continuation of application No. 29/570,107, filed on Jul. 5, 2016, now Pat. No. Des. 805,899, which is a continuation of application No. 14/540,477, filed on Nov. 13, 2014, now Pat. No. 9,517,922, which is a continuation-in-part of application No. 29/509,028, filed on Nov. 13, 2014, now Pat. No. Des. 763,691.

(57) **CLAIM**

The ornamental design for a funnel, as shown and described.

DESCRIPTION

FIG. 1 is a top perspective view of a funnel showing our new design;

FIG. 2 is a bottom perspective view thereof;

FIG. 3 is a top view thereof;

FIG. 4 is a bottom view thereof;

FIG. 5 is a left side view, the right side view being a mirror image thereof; and,

FIG. 6 is a sectional view as seen along line 6-6 of FIG. 5.

1 Claim, 3 Drawing Sheets
